United States Patent Office

Des. 186,634
Patented Nov. 10, 1959

186,634

COMPRESSOR

Edward J. Hildebrandt, Michigan City, Ind., assignor to
Joy Manufacturing Company, Pittsburgh, Pa., a corpora-
tion of Pennsylvania

Application July 31, 1957, Serial No. 47,170

Term of patent 14 years

(Cl. D65—1)

FIG. 1.

FIG. 2.

Figure 1 is a side elevational view of a compressor showing my new design; and

Figure 2 is a top plan view of a compressor as shown in Figure 1.

The dominant features of my design are shown in the drawings by solid lines.

I claim:

The ornamental design for a compressor, as shown and described.
